UNITED STATES PATENT OFFICE

JOHN A. POTTER, OF PITTSBURG, PENNSYLVANIA.

APPARATUS FOR MANUFACTURING HOLLOW METAL ARTICLES.

SPECIFICATION forming part of Letters Patent No. 567,410, dated September 8, 1896.

Application filed July 24, 1893. Serial No. 481,272. (No model.)

To all whom it may concern:

Be it known that I, JOHN A. POTTER, of Pittsburgh, in the county of Allegheny and State of Pennsylvania, have invented a new and useful Improvement in Apparatus for the Manufacture of Hollow Metal Articles, of which the following is a full, clear, and exact description, reference being had to the accompanying drawings, forming part of this specification, in which—

Figure 1 shows my improved apparatus in longitudinal vertical section. Fig. 2 is an enlarged central section of the die and guide-cylinder. Fig. 3 is a cross-section on the line 15 III III of Fig. 2. Fig. 4 is a longitudinal vertical section of a modified form of apparatus, and Fig. 5 is an enlarged partial longitudinal section showing another modification.

The object of my invention is to provide 20 means for manufacturing hollow articles of steel or other metals by forcing the same through a shaping-die while in a plastic or reheated condition.

Various kinds and shapes of articles, such 25 as pipes, axles, shafting, and other hollow articles, may be made in accordance with my invention, and the invention is not limited in its application in this respect.

The apparatus which I show is an improvement 30 upon the apparatus described and claimed in my prior patent, No. 498,304, granted on May 30, 1893.

In the drawings, 2 represents the power-cylinder of a machine, which is made of a 35 strong metal casting, and is preferably connected with an end block 3 by tie rods or bolts 4, which serve to brace the machine and to provide for the resistance of strain.

5 is the plunger of the cylinder 2, and 6 is 40 a pipe by which water or other motive fluid is admitted to the cylinder for the purpose of projecting the plunger. The cylinder is single-acting, and to retract the plunger I employ a smaller counteracting cylinder 7,

45 whose piston or plunger 8 is connected with the plunger 5, so that when the fluid supply is cut off from the pipe 6 the pressure of motive fluid from a pipe 9, acting on the piston 8, will serve to retract the plunger 5 and dis- 50 place the water from the cylinder 2.

11 is the receptacle for containing the steel or other metal to be compressed and shaped.

It consists of a hollow mold-like cylinder which may be encircled by strengthening bands 12, of iron or steel, and which is open 55 at the front end and closed at the rear end. At its opposite sides it has pins or trunnions 13, and it is adapted to sit in a cradle 14, in which it is supported by the fitting of the trunnions in suitable forks. The cradle is 60 swiveled to and supported by the end of the upright plunger 15 of a cylinder 16, which is carried by a truck 17, movable on a track 18. The lower end of the cylinder 16 may be provided with an adjustable stop 19, which 65 limits the extent of downward motion of the plunger 15.

The drawings show the parts of the apparatus in operative position. The mold-cylinder 11 then rests upon the cradle 14, its 70 rear end fits against the end of the plunger 5, and it is connected therewith by pins 20, which fit on hooks 21, projecting from the plunger.

22 is a hollow die which fits in the forward 75 end of the mold-cylinder. It flares internally, and is made of proper diameter and shape to effect the reduction of metal to the required dimension.

23 is a hollow guide box or cylinder set in 80 advance of the die 22 and secured to the end block 3 in line with the axis of the mold-cylinder, so that it shall register with a passage 24 in the end block. The bore of the guide-cylinder is of somewhat larger diameter 85 than the die against which it bears and to which it serves the function of a stationary resistance plate or plunger. In using the word "plunger" to describe this part I intend to indicate that it may be constructed 90 in the manner illustrated or in any other manner adapted to afford resistance to the die, whether the same be merely a passive resistance or whether it be adapted to force the die into the mold-cylinder. 95

25 is a mandrel or rod which extends axially through the plunger of the cylinder 8, through the cylinder 2 and plunger 5, and into the die 22. It is made of somewhat less diameter than the hole in the die, so that 100 there may be an annular space surrounding it at the point where it passes therethrough. The rear end of the rod is preferably supported by a roller 26 or by other suitable

means permitting it to move freely in a longitudinal direction.

The operation of the apparatus is as follows: Before setting the mold-cylinder into the machine, and while it is in an upright position, I prefer to place in its rear end the small charge 27 of refractory clay, which is intended to serve the purpose described in my prior patent, and I then cast or place 10 within the cylinder above the clay a hollow ingot 28. Then when the metal is highly heated, (either reheated or partially solidified from its original molten state,) but is sufficiently solid to permit the mold-cylinder 15 to be placed on its side without bleeding, I suspend it from a crane by means of lugs 29 and lower it into position upon the cradle 14, as shown in the drawings. Before placing the mold-cylinder in the cradle the latter 20 may be raised by elevating the plunger 15, and may then be lowered by exhausting the water from the cylinder 16. The parts are then in the position shown in the drawings, the mold-cylinder being connected with the 25 plunger 5 and the guide-cylinder 23 being in register with the annular die 22. The rod 25 is then inserted through the plungers and through the hollow ingot and into the die, the space within the ingot and around the 30 rod being filled with black-lead, soapstone, or other substance or mixture, which is both refractory and lubricant in its properties and which may be inserted into the ingot before the mold-cylinder is placed in the machine. 35 By use of such refractory and lubricant substance a film is formed between the inside of the ingot and the outside of the rod 25, which performs several important functions. First, acting as a refractory and non-conducting 40 material, it prevents the chilling of the inside of the ingot and prevents the ingot from heating the rod unduly; second, acting as a lubricant, it permits the rod to slide through the ingot, for during the reduction of the 45 metal the rod travels faster than the body of the ingot, as will be shown hereinafter; third, after the hollow article to be made by the machine has been finished the lubricant film prevents the rod from sticking to the 50 metal and enables it to be withdrawn easily. The parts being in the position above described, water is admitted into the cylinder 2 and projects the plunger 5, which, bearing on the mold-cylinder 11, forces it to move forward over the die 22 and over the guide-box or plunger 23. This subjects the metal in the mold-cylinder to powerful compression, and forces it through the die in the annular 55 space around the rod 25, causing it in its 60 passage to assume the form of a hollow cylinder, which is delivered as it is formed into the guide-cylinder 23. As the metal is thus ejected through the die the rod 25 is carried forward therewith by the frictional contact 65 of the flowing metal, and serves constantly as a solid core or mandrel around which the metal is shaped. The projection of the plun-

ger 5 may be continued until the metal has been entirely ejected from the mold-cylinder, the residue remaining in the die being displaced by the refractory material 27, as explained in my prior patent above referred to. When the operation is thus completed, the plunger 5 is retracted by the counteracting-cylinder 7, thereby pulling the mold-cylinder 11 back from the guide-cylinder 23 and leaving the pipe or other hollow article resting in the guide-cylinder. The pipe and rod may then be removed longitudinally and the rod pulled out from the pipe. The mold may be 80 lifted by the cylinder 16, taken out from the machine, another mold-cylinder substituted, and the operations above described repeated in the manufacture of additional articles.

For the purpose of lubricating the action 85 of the die in its motion through the mold-cylinder and in the passage of the metal through the shaping-cavity I place within the mold-cylinder, between its wall and the outer surface of the metal, a film or layer of 90 refractory lubricant, such as described above. As the die is forced inwardly into the mold-cylinder this material lubricates the die in its passage, and as the lubricant is carried by the metal into the cavity of the die it prevents the die from being cut and renders the flowing of the metal easier, reducing the friction to a minimum. To make it convenient to introduce the lubricant into the mold around the metal, an ingot, previously cast 100 in another mold, is used in the mold-cavity, and the ingot is made of tapering form, or smaller in diameter than the mold-cylinder, so as to leave an annular space around the same, into which the lubricant is charged. 105 This lubricant also acts to prevent chilling of the metal and tends to preserve the mold from the effects of excessive heat.

In order to adapt the mold-cylinder 11 for use in combination with rods of different diameters, I prefer to make its rear end of a separate piece having an axial hole for the passage of the rod, so that it can be removed and replaced by other similar pieces when desired.

If desired, the die may also be shaped with suitable longitudinal recesses or projections, so as to impart to the hollow article formed thereby longitudinal ribs or grooves, an article so formed being adapted to be cut into 120 sections and used for gear-wheels; or, instead of using a die circular in cross-section, it may be shaped otherwise, so as to impart any desired sectional shape to the article.

Instead of adapting the machine to the 125 manufacture of pipes which are of uniform diameter throughout, I may use it to make hollow articles whose inside diameter varies at different points, and also hollow articles whose outside diameter is ununiform.

To make pipe with ununiform inside diameter, I simply shape the inner mandrel or rod to conform to the shape and size desired to be given to the different parts of the pipe, as

shown at 25' in Fig. 4, care being taken that it is so shaped as to permit its subsequent withdrawal from the article.

To make a pipe of ununiform outside diameter, (for example, hollow articles whose exterior is provided with stepped portions, like those on large cannon,) I may shape the die so that its orifice shall have a series of steps, as shown at 22' in Fig. 5, and also shape the forward part of the interior of the mold as desired. In using such die I stop the operation of ejecting the metal before it has been entirely displaced, so that the part remaining in the die and in the mold shall have the contour of these parts.

It will be observed and understood by those skilled in the art that modifications such as I have described afford facility for using the principle of my invention in the manufacture of a great variety of hollow articles.

The construction of the apparatus, so that the rod 25 shall travel with the flowing metal, but at a faster rate than the cylinder or plunger which displaces the metal, constitutes a novel and important item of invention. It should be understood, however, that my broader claims are not limited thereto, since, within the scope of the invention as broadly defined, the rod or mandrel, when surrounded with refractory lubricant, may be fixed to or adapted to move with the cylinder or plunger. In such case it is necessary to employ the refractory lubricant material above described, which I claim broadly and without limitation to the manufacture of hollow articles.

In Fig. 2 of the drawings I show passages 31 for water-cooling the die through the guide-cylinder. Other parts of the apparatus may also be water-cooled if desired, and, as will be understood by the skilled mechanic, many modifications in the form, construction, and relative arrangement of the parts may be made without departure from my invention

as defined in the claims, and that novel parts of my invention may be used in other combinations and suitably modified to suit their new relation.

These modification which I have described are not intended to exhaust the enumeration of the possible changes which can be made, but are intended to illustrate such changes and to guide the skilled mechanic in further adaptation of my invention.

I claim as my invention—

1. In apparatus for the manufacture of hollow articles, a receptacle for containing a charge of metal, a hollow die, a longitudinally-movable rod or mandrel extending through the die and receptacle, a body of refractory lubricant surrounding the mandrel within the receptacle, and means for positively forcing the metal charge through the die around the mandrel; substantially as described.

2. In apparatus for the manufacture of hollow articles, a receptacle for the metal, a die through which the metal is ejected, a longitudinally-movable core extending through the receptacle and into the die, and a body of refractory lubricant surrounding the core within the receptacle; substantially as described.

3. In apparatus for the manufacture of hollow articles, a receptacle for the metal, a die through which the metal is ejected, a longitudinally-movable core extending through the receptacle and into the die, and an annular body of refractory lubricant between the charge and the receptacle; substantially as described.

In testimony whereof I have hereunto set my hand.

JOHN A. POTTER.
